UNITED STATES PATENT OFFICE.

MAX LEAF, OF YOUNGSTOWN, OHIO.

BED-CLAMP.

1,392,581.

Specification of Letters Patent. Patented Oct. 4, 1921.

Application filed October 25, 1920. Serial No. 419,507.

To all whom it may concern:

Be it known that I, MAX LEAF, citizen of the United States of America, residing at Youngstown, in the county of Mahoning and State of Ohio, have invented certain new and useful Improvements in Bed-Clamps, of which the following is a specification.

This invention relates to bed clamps.

10 The object of the invention is to provide a cheap and convenient device by means of which the head and foot members of bedsteads may be connected closely together for the purpose of exhibition in salesrooms.

15 Another object is to provide an adjusting means.

A still further object is to provide a brace rod and means of holding the bed clamps from working loose as is quite common with 20 clamps of this class.

My invention seeks to provide a clamp which may be universally applied to all styles of bedsteads, and by means of which two sections of the bed may be strongly and 25 securely connected without danger of breaking or damaging the bed. I attain this end by a specially constructed clamp, which will be fully set forth hereinafter.

Reference is to be had to the accompanying 30 drawings, which illustrate, as an example, the preferred embodiment of my invention, in which:

Figure 1 is a perspective view with clamp in use.

35 Fig. 2 is an enlarged side elevation of the clamps showing the parts of a bed to which the clamp is secured in section.

Fig. 3 is a detail top plan view.

By referring to Fig. 1 it will be seen that 40 I have shown the head section 1 and the foot section 2 of a bed. Secured to the L-shaped base members 3 of the bed will be seen my improved clamp 4. While I have shown but the one clamp it is understood 45 that to properly secure the head and foot sections of the bed a second clamp like the

one shown should be similarly installed at the other end of the L-shaped base members 3.

By referring to Figs. 2 and 3 it will be seen 50 the clamp consists of a plate 5. Secured to this plate 5, by means of a bolt 6, are two clamping members 7 and 8. The clamping members 7 and 8 are provided with slotted openings 9 through which 55 passes the bolt 6. At the outer end of the clamping member 8 is a U-shaped portion 10. At the outer end of the clamping member 7 is a similar U-shaped portion 11. By referring to Fig. 2 it will 60 be seen that the clamping member 7 has a downwardly turned bend at point 12 which allows the L-shaped base member 3 to be clamped between the plate 5 and the clamping member 7 and at the same time allows 65 the clamping members 7 and 8 to be secured underneath the plate 5 and parallel to the plate 5.

At the lower ends of the U-shaped portions 10 and 11 are openings 13 through 70 which passes a brace and securing bolt 14.

It is obvious that when the butterfly nut 15 of the bolt 14 is tightened both arms of the L-shaped base members 3 are forced into a rigidly clamped position.

75 What I claim is:

In a device of the class described, a plate member, a hole centrally located in said plate, two clamping members, U-shaped portions at outer ends of said clamping 80 members, slotted openings at inner ends of said clamping members, a bolt passing through the plate and said slotted openings, openings through the lower ends of said U-shaped portions, a brace and securing bolt 85 extending through said openings, substantially as described.

In testimony whereof I affix my signature.

MAX LEAF.
